UNITED STATES PATENT OFFICE.

ALVAH W. HALL, OF MERIDEN, CONNECTICUT.

ELECTRIC RAILWAY-SIGNAL.

SPECIFICATION forming part of Letters Patent No. 276,807, dated May 1, 1883.

Application filed September 6, 1882. (No model.)

To all whom it may concern:

Be it known that I, ALVAH W. HALL, a citizen of the United States, residing at Meriden, in the county of New Haven and State of Connecticut, have invented new and useful Improvements in Electric Railway-Signals, of which the following is a specification.

This invention relates to an electric railroad-signal which works on a closed circuit, and which, whenever the circuit is broken, falls by its own gravity into sight to indicate danger.

My invention consists in the particular construction and combination of parts, as fully pointed out in the following specification.

This invention is illustrated in the accompanying drawings, in which Figure 1 represents a front view of my signal. Fig. 2 is a sectional side elevation of the same. Fig. 3 is a face view of the reversing-magnet. Fig. 4 is a diagram showing the connection of the several parts with the battery. Fig. 5 is a transverse section of the track, showing one of the track-instruments in elevation, said instrument being the one in which the circuit is normally made and is broken by the passage of the train.

Similar letters indicate corresponding parts.

In the drawings, the letter A designates the signal-disk, which is secured to an arm, B, firmly mounted on a rock-shaft, a, said disk being balanced by a counter-weight, C, so that the disk, when it is left to follow its own gravity, falls down into sight; but very little power is required to raise and retain it in position out of sight. On the rock-shaft a is firmly mounted a pulley, b, which connects by a chain, c, and rod d with a lever, e, that has its fulcrum on a rock-shaft, f, journaled in lugs fixed to the frame D. To this lever, at a point near to its fulcrum, is pivoted a rod, E, the lower end of which is pivoted to the outer end of the armature-lever, F, of an electro-magnet, G, so that when this electro-magnet is vitalized and its armature is attracted the signal A is raised out of sight. An additional counter-weight, H, which is adjustably secured on a lever, I, facilitates the operation of raising the signal. With the armature-lever F is combined a lever, J, which, when the armature is attracted and the signal raised, acts

upon a spring, g, so as to depress its loose end upon a metallic plate, h, Figs. 1, 2, and 4, and bring the binding-posts 10 and 11 in metallic contact. These binding-posts are secured in a board, K, which is fastened to the frame D, and on this board are also secured two binding-posts, 12 and 13, which are insulated from each other. The ends of the helices of electro-magnet G connect with binding-posts 14 and 15, which are supported by the frame D, and are insulated from each other.

The reversing-magnet L, Figs. 3 and 4, is secured to a separate support, M, and its armature-lever N has its fulcrum on a pivot, i. From this armature-lever extend two arms, j k, carrying rollers j' k', and to the arm k is secured a cylinder, l, which engages with a plunger, m, to form an air-cushion, the weight of said cylinder being nearly but not fully counterbalanced by a weight, n, secured to the arm j. The roller j' acts on a contact-spring, o, and the roller k' on a contact-spring, p. The contact-spring o is fastened to a metallic support, 16, and its loose end, when depressed, acts on a metal contact-piece, 17. The contact-spring p is fastened to a metallic support, 18, and its loose end, when depressed, acts on a metal contact-piece, 19.

T T' are the track-instruments, situated on opposite sides of the signal A. (See Fig. 4.) The track-instrument T consists of a spring, which is fastened to a metallic support, 20, and the loose end of which, when in its normal position, bears upon the metallic contact-piece 21. The track-instrument T' consists of a spring, which is fastened to a metallic support, 22, and the loose end of which, when in its normal condition, is out of contact with the metallic contact-piece 23. Any equivalent device may be used in lieu of these springs. The track-instrument T' does not essentially differ in construction from the instrument T illustrated in Fig. 5, the principal difference being that in the former the circuit is normally broken and is made by the passage of the train, while in the latter the circuit is normally made and is broken by the passage of the train.

Each signal has its own battery U. The connections are as follows: The contact-piece 21 of track-instrument T connects by wire 24

with the ground, and the support 20 of the track-instrument connects by wire 25 with the contact-piece 17 of spring *j*' of the reversing-magnet *L*, Figs. 3 and 4. The support 16 of spring *o* connects by wire 26 with binding-post 13, Figs. 1 and 4, and this binding-post connects by wire 27 with binding-post 11, and through the spring *g* (if the signal is raised to "safety") with binding-post 10. This binding-post connects by wire 28 with binding-post 14, and through the helix of electro-magnet *G* with binding-post 15, which connects by wires 29 30 with one pole of battery *U*. The opposite pole of the battery is grounded by wire 34. When the spring of track-instrument *T* is closed down upon contact-piece 21, therefore, the battery-circuit through the electro-magnet *G* is closed, and the signal is maintained in its raised position. When a train approaches in the direction of arrow 1, Fig. 4, the spring *T* is, while the train is passing, raised out of contact with contact-piece 21, the circuit through the electro-magnet *G* is broken, and the signal drops down, showing "danger," so as to protect the first train against a following train until said first train passes the track-instrument *T'*, which is so constructed that its spring is depressed by the wheels of the train against contact-piece 23. At the same time, when the signal shows "danger," the spring *g* recedes out of contact with plate *h* and binding-post 10, Figs. 2 and 4. The support 22 of spring *T'* is grounded, Fig. 4, and the contact-piece 23 connects by wire 31 with helix *L*, and through this helix and wire 30 with battery *U*. The circuit through electro-magnet *L* is closed, the armature *N* is attracted, the roller *K'* depresses spring *p* momentarily against contact-piece 19, and the circuit through signal-magnet *G* is closed through wires 32, binding-posts 14 15, wires 29 and 30 to one pole of the battery *U*, and through wires 33, the ground, and wire 34 to the other pole of said battery. As the armature *N* is attracted by electro-magnet *L* the spring *o* recedes from the contact-piece 17, while the spring *p* also recedes from its contact-piece 19 after having been momentarily closed, as before stated, and the circuit through signal-magnet *G* would be again broken if the track-instrument *T* should from some cause remain closed or the wire 31 become grounded, so that the signal would drop back and show "danger;" but as soon as the outgoing train has passed the track-instrument *T'* the circuit through the electro-magnet *L* is broken, the armature *N* drops back by the weight of the cylinder *l*, the spring *p* is again closed for a short time, the signal is raised to "safety," the springs *g* and *o* are closed down, and the circuit through the signal-magnet *G* is closed through wire 24, track-instrument *T*, wire 25, spring *o*, wire 26, binding-post 13, wire 27, binding-posts 11 and 10, wire 28, binding-post 14, helix *G*, binding-post 15, wires 29 and 30, battery *U*, and wire 34. The signal shows "safety" until the spring of the track-instrument *T* is again raised by the wheels of

the next train. By the air-cushion *l m* the motion of the armature *N* in falling back is retarded, and the spring *p* is closed sufficiently 70 long to raise the signal to "safety."

If desired, a secondary signal (either audible or visible) may be connected with the main signal *A*, and located at a suitable distance in front of said main signal, so as to indicate to 75 the engineer of an incoming train the position of the main signal before he reaches it. Another secondary signal may be placed at a distance behind the main signal to inform the engineer of the passing train if the apparatus is 80 in proper working order. By this combination I am enabled to indicate to the engineer on each train if it is safe for him to proceed, or if there is a train ahead, and unless the position 85 of my signals is disregarded the danger of running one train into another is absolutely avoided.

What I claim as new, and desire to secure by Letters Patent, is—

1. The combination, substantially as herein-before described, of a signal constructed to be maintained in a position indicating "safety" by an electro-magnet, and to drop into a position indicating "danger" by its own gravity, a signal-magnet which, when vitalized, maintains the signal in a position indicating "safety," a track-instrument which in its normal condition is closed and forms part of the circuit through the signal-magnet, and which is opened by the wheels of a passing train, a spring, *o*, which, when closed, forms part of the circuit of the signal-magnet, a reversing-magnet, the armature-lever of which closes said spring when the magnet is not vitalized, and a battery, the electric connections being from the track-instrument *T* through the spring-contacts *o* and *g*, the signal-magnet, and thence to battery and ground. 95

2. The combination, substantially as herein-before described, of a signal constructed to be maintained in a position indicating "safety" by an electro-magnet, and to drop into a position indicating "danger" by its own gravity, a signal-magnet which, when vitalized, maintains the signal in a position indicating "safety," a track-instrument which in its normal position is closed and forms part of the circuit through the signal-magnet, and which is opened by the wheels of a passing train, a lever, *J*, which is actuated by said signal, a spring, *g*, which forms part of the circuit of the signal-magnet when the signal occupies a position indicating "safety," a spring, *o*, which, when closed, forms part of the circuit of the signal-magnet, a reversing-magnet, the armature-lever of which closes said spring when the magnet is not vitalized, and a battery, the electric connections being from the track-instrument *T* through the spring-contacts *o* and *g*, the signal-magnet, and thence to battery and ground. 110 115 120 125

3. The combination, substantially as herein-before described, of a signal constructed to be maintained in a position indicating "safety" by an electro-magnet, and to drop into a posi- 130

tion indicating "danger" by its own gravity, a signal-magnet which, when vitalized, maintains the signal in a position indicating "safety," a track-instrument which in its normal condition is closed and forms part of the circuit through the signal-magnet, and which is opened by the wheels of a passing train, a spring, *p*, which, when closed, forms part of the circuit through the signal-magnet, a reversing-magnet, the armature-lever of which closes said spring momentarily when the magnet is vitalized, and a battery, the electric connections being through track-instrument T, spring-contacts *o* and *g*, through signal-magnet, and thence to battery and ground, thence through track-instrument T' and reversing-magnet L to battery and ground.

4. The combination, substantially as hereinbefore described, of the reversing track-instrument T', the reversing-magnet L, the armature-lever N, contact-springs *o p*, actuated by said armature-lever, the signal-magnet G, signal A, and battery U.

5. The combination, substantially as hereinbefore described, of the track-instrument T, signal A, signal-magnet G, reversing track-instrument T', reversing-magnet L, armature-lever N, contact-springs *o p*, actuated by said armature-lever, and battery U.

6. The combination, substantially as hereinbefore described, of the track-instrument T, signal A, signal-magnet G, contact-spring *g*, actuated by the armature-lever of the signal-magnet, reversing track-instrument T', reversing-magnet L, armature-lever N, contact-springs *o p*, actuated by said armature-lever, and battery U.

In testimony whereof I have hereunto set my hand and seal in the presence of two subscribing witnesses.
